ELECTROMECHANICAL SIGNALING
DEVICE

Herbert F. Obergfell, River Forest, Ill., assignor,
by mesne assignments, to Associated Electric
Laboratories, Inc., Chicago, Ill., a corporation
of Delaware

Application May 23, 1930, Serial No. 455,012

3 Claims. (Cl. 177—328)

The present invention relates in general to electromechanical signaling devices, but is particularly concerned with the provision of devices of this character which, owing to the functions 5 they are required to perform and the limited amount of space they are permitted to occupy, make it necessary that they be very compact, and at the same time very reliable in operation.

As an example, the system disclosed in White 10 application, Serial No. 425,121, filed February 1, 1930, discloses an electric display board for a system of power distribution in which display board miniature lamp signals are used extensively. The signal devices illustrated in the 15 present application are considered to be much more desirable for certain types of installations than signals of the lamp type and are compactly designed to replace lamp signal devices, such as illustrated in the White application.

20 The invention is disclosed in a single sheet of drawing comprising Figs. 1 to 9, inclusive, illustrating various views of the signaling devices of the invention.

Fig. 1 is a front view of the device, in elevation; 25 Fig. 2 is a side view; Fig. 3 is a rear end view; Fig. 4 is a side view; Fig. 5 is a side view, of a portion of the device as seen in Fig. 4, but with certain portions broken away to more clearly show the operating mechanism; Fig. 6 is a similar view 30 to Fig. 5, but shows a modified form of the device; Fig. 7 is a bottom view; Fig. 8 is an enlarged view of the portion of the device shown in Figs. 1 to 5 and 7, while Fig. 9 illustrates the markings on the periphery of the cylinder 11 of the device.

35 The device as illustrated in Figs. 1 to 5, inclusive, and 7 is of the multi-position type. The frame member 1 serves as a support for the assembly. This frame member is made of light gauge sheet iron, perforated and bent into the 40 form of a bracket appropriate for receiving the miscellaneous other elements which make up the device. It will be observed, upon examination of Figs. 1, 2, 4, 7, and 8 that free ends 6, 7, and 45 6', 7' of frame or support 1 are brought together. These free ends are spot welded so as to make the support a rigid structure.

50 Secured within the confines of the support 1 at one end thereof is an operating magnet 2, which is held in place by a stud 19 threaded into the core of the magnet 2. A terminal assembly having four terminals 5, mounted on an insulated disc 4 is also held in spaced relation to the support 1 by the spacer 3, stud 19 and nut 18.

55 Adjacent the free end of the magnet 2, and in operative relation with the core thereof, is an

armature 14. This armature is mounted in pivoted relation to the support 1 through the medium of lugs 20 and a perforation in the side of the support which is visible in Fig. 4 and the shaft 22.

Secured to a sleeve member 41, shown in Fig. 7, 60 is a drum 11, ratchet wheel 25, and a spring operating cam 40. These elements are all spaced in fixed relation to the sleeve and held in place in the support by a shaft 10. This shaft, as well as shaft 22, is riveted in fixed relation to the 65 frame.

An operating pawl 15, in pivoted relation to the armature 14, links the ratchet wheel in operative relation with the armature. A combined armature and pawl back stop 23 is keyed to the support 1 and held thereto, in properly adjusted relation to the pawl, by screw 24.

Mounted upon the support 1, intermediate to the drum 11 and armature 14, is a pair of contact springs 12 and 13 having upwardly extending 75 terminals 12' and 13'. These springs are held in place by the bracket 26, into which are threaded the screws 33. A helical spring 9 links the armature 14 to the bracket 26 and functions to hold the armature 14 away from the pole piece of the 80 magnet 2; while a helical spring 8 extending between the bracket 26 and pawl 15 serves to hold the pawl tensioned against the ratchet wheel 25.

The device, when wired for operation, has the winding of magnet 2 connected to two of the 85 terminals 5, while the springs 12 and 13 have their terminals 12' and 13' connected with the remaining pair of terminals 5.

The device is arranged to be supported by the face portion 17 and its associated lugs 16 in substantially the same manner as are the lamp signal units disclosed in the former application referred to. 90

It will be observed that the ratchet wheel 25 has eight teeth and, therefore, eight operations 95 of the magnet are required to rotate the cylinder or drum 11 one revolution.

As will be observed from Fig. 9 the circumference of the drum 11 has four divisions each of different colors. As will be observed from Fig. 1 100 the face portion 17 of the support 1 has a window or opening therein through which the drum extends. At this opening one division of the drum is visible, and may show one solid color portion of the drum, or portions of two colors. 105 Therefore, since the ratchet wheel 25 has eight teeth it is possible to display eight signal combinations. With the color scheme illustrated in Fig. 9, these combinations would be red, red yel- 110

low, yellow, yellow blue, blue, blue green, green, and green red, respectively.

As illustrated in Fig. 5, the cam 40 is arranged to close the associated springs 12 and 13 in but 5 one of the eight positions of the cylinder or drum 11, but obviously, by modifying the cam the spring combination may be closed at other positions as well. The springs 12 and 13 may be utilized to control circuits or apparatus located 10 at a point remote from the signal.

Under certain circumstances it is desirable to provide a signal interchangeable with and having the same appearance to the observer as the signal just described, but arranged to give but two 15 indications in conjunction with the performing of a circuit switching operation in one of such positions. The arrangement shown in Fig. 6 meets this requirement and, except for the omission of the pawl and ratchet mechanism and the 20 substitution of a modified connection between the magnet and the drum, is like the former mechanism. The armature 34 is mounted in the same manner as the armature 14. A bracket 31 is substituted for the bracket 26 and has an 25 upwardly extending element 50 which serves as a back stop for the armature 34. Spring 32, connected between the bracket 31 and the armature 34, functions to hold the armature away from the core of the magnet 2.

30 Secured to the cylinder or drum 11', in substitution of the ratchet wheel 25, is a spacer block 36. The armature 34 is linked to the drum 11' through the medium of link 35, one end of which is pivoted to the block 36 by pin 37, while 35 the other end is pivoted to the armature 34 by pin 38. Upon energization of the magnet the armature 34 carries with it the link 35 which brings about the rotation of the drum 11 for a sufficient distance to completely change the 40 surface of the drum 11 exposed through the opening in the face 17. This rotation also causes the cam 40 to operate its associated springs. Upon de-energization of the magnet the spring 32 causes 45 the armature, drum, and springs to restore to their initial position.

From the foregoing it will be appreciated that applicant has succeeded in designing a compact form of signaling device which may be readily constructed and which will be reliable in operation.

50 What is claimed is:

1. In a magnetic device, a sleeve having a ratchet wheel and spring operating cam thereon, a pawl for rotating said wheel, a magnet having 55 an armature operable thereby to actuate said pawl, a spring pile-up including a pair of contact springs one of which is so mounted that it is

movable into engagement with the other by said cam, springs connected with said pawl and armature, respectively, to hold the pawl in operative relation to said ratchet wheel and the armature away from said magnet, means included in said pile-up for holding said last springs under tension comprising a bracket perforated to receive such springs, and another spring included in said pile-up engaging and holding said ratchet wheel against retrograde movement during the operation of said pawl.

2. In a signal device, an electromagnet, an armature, means for mounting said armature in co-operative relation to said magnet; a shaft on which is mounted a display drum, a ratchet wheel, and a cam; a frame, means for supporting the shaft and said electromagnet to said frame, a pawl, means for mounting said pawl to be actuated by said armature to actuate said ratchet wheel, a spring, means mounting said spring for holding said pawl in engagement with said ratchet wheel, a second spring, means mounting said second spring to bias said armature away from said electromagnet and to move said pawl in ratchet actuating direction, two leaf springs, co-operating contacts on said leaf springs normally spaced apart, one of said leaf springs so mounted as to be moved by said cam that said contacts engage, a leaf spring for preventing retrograde movement of said ratchet wheel, a spring pile-up including said leaf springs and a bracket, and means for securing one end of the holding springs to the bracket.

3. In a display device; a frame member having an assembly rotatably mounted on one end thereof comprising a shaft supporting an indicating drum, a contact spring actuating cam, and a ratchet wheel, respectively; an auxiliary assembly including a pair of contact springs, mounted on said frame, one of which is so positioned as to be operated by said cam into engagement with the other, an electromagnet, means for securing said electromagnet to the other end of said frame, an armature; means for pivoting said armature to said frame, at a point intermediate to said assembly and electromagnet, and in operative relation to the latter; an operating pawl for the ratchet wheel, means for pivoting said pawl to the free end of said armature; and a pair of springs linked between said auxiliary assembly and said pawl and armature, respectively, to normally hold said armature away from said electromagnet and said pawl constantly in engagement with said ratchet wheel.
